UNITED STATES PATENT OFFICE.

JAMES MARION DAVIS, OF NEWBERRY, SOUTH CAROLINA.

LOOM COUNTER.

Application filed January 14, 1926. Serial No. 81,282.

This invention relates to counters such as are used for counting revolutions or other movements of a shaft or other mechanical element and particularly to counters for use in connection with looms, for the purpose of counting the number of revolutions of certain parts and the amount of work turned out by a loom.

There are on the market at the present time many loom counters of varying designs. All double counters, however, which are on the market for use on looms are of a non-resetting type and are operated by means of complicated and expensive worm gear mechanism having little durability and presenting many difficulties in attachment to or engagement with loom shafts from which they derive their power. As far as I know, no double counter, designed for registering or indicating separate shift services or separate totals and having independent resetting features has been devised. A counter for looms has been designed which admits of being set back to zero but in this form of counter the shaft of the counter is revolved at a relatively high speed or has a continuous revolution and this makes it of little durability on looms where shaft speeds are normally from 160 to above 200 R. P. M.

One of the objects of the present invention is to provide in connection with a counter of the resetting type, mechanism which will cause the motion of the counter to be much slower than is possible where the counters are driven in synchronism with loom shaft speeds.

A further object is to provide a mechanism of this character which is extremely simple and which may be easily installed by simply bolting it on a convenient portion of the loom frame and connecting the actuating lever of the counter to any desired revolving or reciprocating part of the loom or other mechanism.

A further object of the invention is to provide a double counter which includes a plurality of sets of relatively independent dial wheels, each set being capable of individual resetting independently of the other set and provide manually shiftable means whereby either set may be driven from a single actuating shaft, thus permitting the counters to indicate the amount turned out by two shifts of operators, and enable employers to know at a glance how each machine is being operated and how much product has been turned

out since the counter has been reset and thus, indicate at all times the exact individual production of all machines and the comparative production of two shifts of operators. 60

A still further object is to provide a double counter embodying a plurality of sets of relatively independent dial wheels, each set being capable of independent resetting and providing means whereby both sets of dial wheels may be operated simultaneously at different speeds so that the counters will show, on one set, the production of the machine to which the counter is attached in yards, picks, revolutions or otherwise, and 70 on the other set the amount of money, for instance, earned by the machine during any period.

Other objects will appear in the course of the following description. 75

My invention is illustrated in the accompanying drawings wherein:

Figure 1 is an end elevation of a loom counter constructed in accordance with my invention; 80

Figure 2 is a front elevation thereof, the housing of the counter being in section;

Figure 3 is a top plan view of the structure shown in Figure 2, the housing being in section; 85

Figure 4 is an end elevation of the construction shown in Figures 2 and 3, the pins 29 being in section;

Figure 5 is a like view of Figure 4, but showing the pawl raised by the member over 90 which the pawl rides;

Figure 6 is a fragmentary top plan view showing a modified arrangement of the operating mechanism;

Referring to these drawings it will be seen 95 that the base of the machine comprises a base plate 10 having upwardly extending supporting walls 11, 12 and 13 extending longitudinally and supporting bearings. Mounted in all three of these walls is a primary 100 or actuating shaft 14, this shaft preferably extending out at its opposite ends beyond the walls 11 and 13 so that an actuating crank or lever 15 may be attached to either end of the shaft to oscillate therewith. 105 Mounted in the wall 12 are two shaft sections 16 and 17. The shaft section 16 carries upon it a gear wheel 18 and the shaft section 17 carries upon it the gear wheel 19, these gear wheels being offset, or in 110 other words, not being in the same plane. Mounted upon the shaft 14 is a pinion 20

- which, as illustrated, is carried by a tubular hub 21 of the ratchet wheel 22 and the ratchet wheel 22 and the pinion 20 rotate loosely upon the shaft 14 but are shiftable 5 longitudinally upon the shaft 14 to thereby carry the pinion 20 into engagement with the wheel 18 or with the gear wheel 19 as desired. This is accomplished by means of a shifting fork 23 which extends on each 10 side of the ratchet wheel 22 and has a button 24 which extends outward to the front of the machine whereby the pinion may be shifted into engagement with either of the gear wheels 18 or 19.
- 15 Mounted upon the shaft 14 for movement therewith, is an arm 25 which has at its end an outwardly projecting pin 26 and mounted upon this pin is a pawl 27, this pawl having a width greater than the width 20 of the ratchet wheel 22 so that though the ratchet wheel be shifted to carry the pinion 20 into engagement with either gear wheel 18 or 19, yet the pawl 27 will be at all times in engagement with the ratchet wheel 22.
- 25 Extending transversely across the machine inward of the arm 25 is the pawl guard 28 which is mounted upon pins 29 projecting from the wall 11. This pawl guard comprises a plate, the upper edge of which is so 30 formed that the pawl 27 rests at all times against the upper edge of the pawl guard but prevents the pawl from engaging with the ratchet wheel except during a certain portion of the travel of the pawl. To this 35 end the upper surface of the pawl guard is formed with a medially disposed upwardly rounded portion 30 and towards the front of the machine and at the end of this rounded portion with a slight projection or stop 40 31, the upper face of which is slightly inclined upward. As the pawl moves forward it will keep in contact with a tooth of the ratchet wheel until the forward edge of the pawl strikes this projection 31 and on further movement the pawl will ride up the inclined face of the projection 31 and off of the ratchet tooth with which the pawl has 45 been engaged. It will be obvious now that as the shaft 14 is oscillated by connecting 50 the arm 15 to any suitable part of the loom, the ratchet wheel, of course, and the pinion 20 will be given a step by step movement of rotation in one direction and this will be transmitted to one or the other of the gear 55 wheels 18 or 19 as the case may be, and thus one or the other of the sets of indicating dials or counting dials mounted upon the shaft section or coating with the shaft sections 16 and 17, will be operated.
- 60 I do not wish to be limited to any particular counting mechanism or registering mechanism except in so far as each set of counting mechanism must be capable of being reset independently of the other set of counting mechanism. Each set of counting
- mechanism is the same as the other set and, therefore, description of one will apply to the other. For instance, on the shaft section 16 there is mounted a disk 32 having in its periphery a notch 33. Mounted for 70 rotation around the same axis are a plurality of counting wheels 34 each having peripherally disposed numbers, and each counting wheel on one side is formed with a gear wheel 35 and on the other side with a radial notch 36. Extending parallel to the axis of the counting wheels 34 is a shaft 37 carrying upon it a plurality of pinions 38, certain of the teeth of each pinion being 75 transversely elongated so as to engage with the teeth of wheel 35 and also to be engaged by the notch 36 of the preceding dial, the first pinion of the series engaging the gear teeth of that wheel 35 and also being adapted to be engaged by the notch 33 of the disk 32. Thus it will be obvious that when the disk 32 has made one revolution it will shift the corresponding pinion 38 one step and this will shift the first dial wheel of the series one step and then when the first dial wheel of the series has made a complete revolution, the notch 36 will engage with the next succeeding pinion 38 and rotate that one step to cause a one step revolution of the 80 next succeeding dial and so on.
- 85 In order to prevent reverse motion of the ratchet wheel I provide a spring pawl 39, illustrated as mounted upon the base and engaging said ratchet wheel. This pawl may be made wide enough to engage the ratchet wheel in either of its two positions.
- 90 Attention is called to the fact that as shown in Figures 4 and 5 the pawl guard 28 not only prevents the pawl 27 from continuing in engagement with a tooth of the ratchet wheel 22 on its forward movement beyond a predetermined point but that the rear end of the pawl guard constitutes a 95 stop against which the pin 26 strikes when the arm 25 is moved back a predetermined distance, thus the arm 25 may be given a stroke just equal to one tooth of the ratchet wheel 22 or may be given a stroke greater than this without, however, actuating the ratchet wheel 22 more than one step on an 100 oscillation of the arm. This permits this device to be applied to machines in which the operating member to which the lever 15 is connected to have different strokes without, however, causing more than a one step movement of the ratchet wheel 22.
- 105 In Figure 6 I have illustrated a construction which, in most respects is the same as that shown in Figures 2 and 3, except for the fact that the actuating pinion is in engagement with both dial wheel carrying shafts at the same time. I have designated the dial wheel carrying shafts as 16^a and 17^a. The actuating shaft is designated 14^a and 110 carries upon it the loose pinion 20^a and the 115
- 120
- 125
- 130

ratchet wheel 22^a. The gear wheel 18^a is relatively large and the gear wheel 19^a is relatively small, thus causing the counting dials on the shaft 16^a to be driven at a slower speed than the dials on the shaft 17^a. Thus these shafts will be driven at different ratios.

The mechanism for driving the ratchet wheel 22^a is the same as the mechanism previously described and comprises the arm 25 mounted upon the shaft 14^a, the pawl 27 on the arm and the pawl guard 28. It will be seen that with this mechanism oscillations given to the shaft 14 will be transmitted to the ratchet wheel 22^a and thus to the pinion 20^a and the gear wheels 18^a and 19^a will be given a step by step movement in one direction which will cause the step by step advance of the dials 34 of the two series 20 of registering devices.

While I do not wish to be limited to any specific mechanism for resetting the dial wheels I have illustrated a construction wherein the dial wheels of each set are reset to zero by means of a key inserted into a keyhole 40 in an arbor 41. This is a common and well known resetting means such as is found in a large number of different counting mechanisms and requires no particular 30 description.

I claim:—

1. A mechanism of the character described including an actuating rock shaft, a ratchet wheel loosely mounted thereon, an arm carried and oscillated by the actuating shaft and having a pawl engaging with said ratchet wheel and a bar supported in chordal relation to the ratchet wheel and having its outer edge face outwardly curved, said edge face at one end of the bar being extended beyond the ratchet teeth and at the

other end of the bar being disposed inward of the ratchet teeth, and then extending beyond the ratchet teeth, the pawl traveling over said curved face of the bar whereby to hold the pawl from engagement with the ratchet teeth for the greater portion of its stroke, then permit the engagement of the pawl with the ratchet teeth and then again lift the pawl after the pawl has traveled at 50 a predetermined distance in said engagement.

2. In a mechanism of the character described, a pair of shafts, each shaft having a gear wheel, the gear wheels being disposed out of alignment with each other, a ratchet wheel carrying a pinion and shiftable to carry the pinion into engagement with either of the gear wheels, means for shifting the pinion and ratchet wheel into such engagement and an oscillatable arm having a pawl engaging the ratchet wheel, the pawl having a width greater than the range of movement of the ratchet wheel whereby the pawl may engage the ratchet wheel in either position thereof. 55

3. In a mechanism of the character described, a pair of shafts, each having a gear wheel, an operating shaft having means whereby it may be oscillated, a ratchet wheel and a pinion together slidably mounted 70 upon the operating shaft to thereby carry the pinion into engagement with one or the other of the gear wheels, means on the operating shaft for giving a step by step motion to the ratchet wheel in either of its 75 positions, and a shifting device operatively engaged with the ratchet wheel and pinion, and having a manipulating member connected thereto.

In testimony whereof I hereunto affix my 80 signature.

JAMES MARION DAVIS.
